STEADY REST FOR LATHES

Walter F. Liber, Meriden, Conn.

Application November 1, 1943, Serial No. 508,497

3 Claims. (Cl. 82—38)

This invention relates to lathes, and more particularly to a device for steadyng a rotating work piece while it is being operated upon by the cutting tools of a lathe.

In turning wood or metal, difficulty is frequently experienced in preventing the work from springing away from the tool. As the material thus springs and bends, it is apt to slip off the lathe centers, cause "chattering," and produce uneven, irregular and rough surfaces on the work. By means of the present invention the above and other objections have been avoided.

One object of the present invention is to provide a lathe steady rest of the above nature, having a plurality of sliding finger pieces, which are adapted to engage the work when the tool is operating adjacent the tailstock of the lathe, and which finger pieces will be retracted when the steady rest is located near the central portion of the work.

A further object is to provide a steady rest of the above nature in which each finger piece is carried by a slide plate mounted in a radial yoke carried by the supporting block of the steady rest.

A further object of the present invention is to provide a steady rest of the above nature, which will be simple in construction, inexpensive to manufacture, easy to install and manipulate, compact, ornamental in appearance, and very efficient and durable in use.

With these and other objects in view, there has been illustrated on the accompanying drawing one form in which the invention may conveniently be embodied in practice.

In the drawing,

Fig. 1 represents a side view of a lathe upon which the present invention has been installed, the steady rest being shown located adjacent the tailstock, and the spindle of the latter being out of engagement with the work.

Fig. 2 is a sectional view of the same, taken along the line 2—2 of Fig. 1, looking in the direction of the arrows.

Fig. 3 is a detail sectional view of Fig. 2, taken along the line 3—3 of Fig. 2, looking in the direction of the arrows.

Fig. 4 is a detail view of a portion of the finger plate showing the finger piece projecting outwardly therefrom.

Referring now to the drawing, in which like reference numerals denote corresponding parts throughout the several views, the numeral 10 indicates a lathe bed, upon which are mounted a headstock 11 and a tailstock 12, provided with

work engaging spindles 13 and 14 respectively. The headstock is also provided with a face plate 15 having a slot in its periphery for receiving a finger 16 of an angular dog member 17. The dog member 17 is adapted to be held securely upon a work piece 18 by means of a set screw 19, as clearly shown in Fig. 1.

The steady rest, forming the subject of the present invention, is shown at the right of Fig. 1, at the hollow end of the cylindrical work piece 18, and said steady rest comprises a two-part holding block 20. The bottom portion of the block 20 is provided with a flat guide foot 21 and a V-grooved foot 22, which feet 21 and 22 are adapted to rest upon a flat guide face 23 and a V-shaped guide rib 24 respectively, forming part of the lathe bed 10, as shown in Fig. 2.

The feet 21 and 22 of the holding block are connected together by a horizontal crossbar 25 through which passes a vertical clamping bolt 26 having a bottom head 27 seated within a recess in a bottom cross-shoe 28. The adjusting bolt 26 is provided on its upper end with a nut 29 which is adapted to tightly engage the crossbar 25 to clamp the block in any desired adjusted position along the length of the lathe bed.

Located within the holding block 20, which is preferably substantially circular in shape, are three rectangular finger plates 30, 31, 32, arranged in equally spaced radial relationship around the periphery of the work 18, said plates being slidably mounted within three outstanding yokes 33, 34, 35, also radially arranged. At the inner ends of the finger plates 30, 31, 32 provision is made of three work-engaging flat finger pieces 36, 37, 38, the outer ends of which are curved at 39, for a purpose to be hereinafter described. The finger pieces 36, 37, 38 are provided with two sets of aligned short slots 40, 41, located at the outer and inner ends of said finger pieces respectively. Within the slots 40, 41 are located pairs of screws 42, 43 for clamping the finger pieces 36, 37, 38 in adjusted position. The finger plates 30, 31, 32 are each provided with radial slots 44, 45, 46 within which the finger pieces 36, 37, 38 are adapted to slide. The slots 44, 45, 46 of the finger plates are also adapted to embrace crossbolts 47, 48, 49 respectively, which are provided with flanged heads 50, 51, 52 adapted to seat on the front of the finger plates 30, 31, 32. The rear sections 53, 54, 55 of said bolts 47, 48, 49 are threaded and screwed into tapped holes 56 in the yokes 33, 34, 35. The curved ends 39 of the finger pieces 36, 37, 38 avoid interference with the bolts 47, 48, 49.

In order to hold the finger pieces 36, 37, 38 against the work 18 in any desired adjusted position, provision is made in the yokes 33, 34, 35 of a plurality of outstanding adjustable radial screws 57, 58, 59 located in tapped holes 60, and carrying square heads 61, 62, 63 on their outer extremities.

Provision is also made of a pivot pin 64 for hinging the upper portion of the holding block 20 to the lower portion of said block. The free end of the upper portion of said block is connected to the lower portion thereof by means of a locking bolt 65 pivoted at 66 to said bottom portion, and having a lock nut 67 seated upon a washer 68 located upon an outstanding ear 69 formed integral with said upper portion.

Operation

In the operation of the present invention, when the steady rest is to be used to guide the center of a rotating work piece, which is supported at both ends by the headstock spindle 13 and the tailstock spindle 14, the small finger pieces 36, 37, 38 will be retracted in their plates 30, 31, 32, and the latter plates will directly engage the rotating work piece 18. When, however, the holding block 20 is located at the right hand end of the work, the tailstock spindle 14 will be separated a considerable distance from the end of the work 18, and will therefore be idle. In the latter case, the finger pieces 36, 37, 38 will be slid inwardly into engagement with the end of the work and will be held in such position while the work is being machined.

While here has been disclosed in this specification one form in which the invention may be embodied, it is to be understood that this form is shown for the purpose of illustration only and that the invention is not to be limited to the specific disclosures, but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. The combination with a lathe including a headstock having a center point therein for mounting and supporting one end of a workpiece, of a mounting for axially and rotatably support-

ing the other end of the workpiece, said mounting comprising a two-part holding block supported upon the lathe bed, means to hold said block in adjusted position along the length of said bed, 5 said block having a plurality of radial yokes, a plurality of slotted plates carried by said yokes, the inner ends of said plates arranged to engage said workpiece and prevent radial play thereof, the inner ends of said plates being also provided with adjustable work-engaging finger pieces located in the slots of said plates and extending beyond said inner ends and arranged to engage the end of said workpiece to prevent axial play thereof, and screw means to clamp each of said finger pieces in position within its respective plate.

2. In a steady rest for a lathe in which the workpiece is mounted on the headstock center point, a two-part holding block adjustably supported upon the lathe bed, said block having a plurality of radial yokes, a plurality of slotted plates adjustably carried by said yokes to prevent radial play in said workpiece, the inner ends of said plates being provided with adjustable work-engaging finger pieces located in the slots of said plates for preventing axial play of said workpiece, screw means to clamp each of said finger pieces in position within its respective plate, and cross bolts for locking said plates to said yokes, said finger pieces being provided with curved outer ends for embracing said cross bolts.

3. In a steady rest for a lathe in which the workpiece is mounted on the headstock center point, a two-part holding block adjustably supported upon the lathe bed, said block having a plurality of radial yokes, a plurality of slotted plates adjustably carried by said yokes to prevent radial play in said workpiece, the inner ends of said plates being provided with adjustable work-engaging finger pieces located in the slots of said plates for preventing axial play of said workpiece, screw means to clamp each of said finger pieces in position within its respective plate, and cross bolts for holding said plates within said yokes, said cross bolts having heads formed thereon, which heads are provided with flanges for engaging said finger pieces to hold them in operating position.

WALTER F. LIBER.
